SPRING LINER ASSEMBLY

Newton E. Shockey, Detroit, Mich., assignor to
 Van Dresser Specialty Corporation, Van Dyke,
 Mich., a corporation of Michigan

Application August 4, 1948, Serial No. 42,463

2 Claims. (Cl. 155—181)

1

This invention relates to improvements in spring liner assemblies.

An object is to provide an improved spring liner assembly which is so constructed as to prevent the wadding or cotton batting from being forced downwardly into the spaces between a coil spring assembly which supports the entire upholstery of a spring cushion such as the seat or back cushion of a motor vehicle; which spring liner assembly is of simple construction, inexpensive to fabricate and consists of a minimum amount of material.

Heretofore spring liners have been provided wherein a plurality of reinforcing stiffening members which were generally short sections of spring wire were held in spaced apart substantially parallel relationship in a row by a sheet of fabric to which the sections were secured as illustrated in applicant's issued Patent No. 2,423,159, July 1, 1947. Such spring liner was interposed underneath the wadding and upholstery material and overlying the spring assembly as shown in said patent.

The present invention consists in a provision of a spring liner adapted to serve the purposes of the conventional spring liners of commerce and which employs a minimum amount of material and is inexpensive as to cost.

Another object is to provide a spring liner of the character above described which is adapted to be secured to and form a part of an overlying layer of cushion forming material for application therewith to the spring assembly in the building up of the spring cushion.

Other objects, advantages and meritorious features of my invention will more fully appear from the following description, claims and accompanying drawings wherein;

Fig. 1 is a perspective of a fragment of a vehicle seat cushion assembly embodying this invention.

Fig. 2 is a cross-sectional view through the upholstery material seated upon the spring assembly.

Fig. 3 is a cross-sectional view through the spring liner showing a fragment thereof.

Fig. 4 is a cross-sectional view similar to that of Fig. 3 showing a modification thereof.

Fig. 5 is a perspective of a fragment of my spring liner shown in Fig. 3.

Fig. 6 is a plan of a fragment of a cushion assembly showing a modification of my spring liner and with the upholstery material which is superimposed upon the liner removed.

Fig. 7 is a view similar to that of Fig. 6 showing a modified form of liner.

2

Fig. 8 is a sectional view taken on the line 8—8 of Fig. 7 but showing the upholstery material which is not shown in Fig. 7.

Fig. 9 is a fragmentary cross-sectional view taken on the line 9—9 of Fig. 7.

Fig. 10 is a perspective of a fragment of the liner shown in Fig. 6.

Spring liners of the character herein described are generally used in spring cushion assemblies being interposed between the wire spring assembly and the overlying layers of cushion forming material. These overlying layers of cushion forming material include a layer of wadding or cotton batting. The liner is provided to prevent this wadding from being pushed into the spaces between the coil springs. In the assembly shown in Fig. 1 there is a wire spring assembly which is made up of a plurality of conventional coil springs 20 which are here shown as of the hour-glass type. These springs are mounted within and between upper and lower boundary frame wires 22 and 24. They are secured to the boundary wires and to each other by wire clips commonly referred to in the industry as hog rings 26. Certain of these coil springs 20 may be enclosed within fabric pockets 28.

This complete spring assembly is overlaid with layers of cushion forming material. A conventional arrangement is shown in Fig. 1, conventional except for my improved liner, wherein there is an overlying layer of upholstery fabric or covering material 30. Underneath this outer layer of upholstery fabric, there is a layer of wadding or cotton batting 32. A layer of fabric 34 such as a netting may be spread over the layer of wadding underneath the upholstery fabric. The wadding may itself be secured to or overlay another layer of fabric such as burlap indicated as 36. These different layers of material are stretched over the wire spring assembly and down over the sides and ends thereof and secured to the underside of the spring assembly in any suitable conventional manner.

My improved spring liner is shown as interposed between the several layers of upholstery material and the wire spring assembly. This spring liner consists of a plurality of reinforcing stiffening members 38 placed in a row in substantially parallel spaced apart relationship as shown in the drawings. This row of members is held together in such spaced relationship and is carried by a pair of flexible longitudinal strips 40 which extend along the ends of the members 38 and to which these members are secured. These members 38 may be formed of short lengths of spring wire. The strips 40 may be

formed of burlap or other suitable flexible material. In Figs 1 through 5 of the drawing each burlap strip 40 is shown as folded over along one margin as at 42 providing a marginal fold about which the ends of the wires 38 are bent as at 44 as shown in the drawing. This spring liner is adapted to be secured to the under surface of the burlap sheet 36 by a suitable adhesive. In Fig. 5 the upper surface of the strip 40 is shown as coated with adhesive such as latex 46. Both strips 40 are so coated. These coated surfaces of the strips 40 are secured to the under surface of the burlap sheet 36 and cured thereon so as to form secure adhesion.

If desired, the spring liner may be secured directly in a similar manner to the underside of the layer of wadding 32 without the interposition of the burlap sheet 36. When so secured to an overlying layer of cushion forming material, whether the wadding layer 32 or the burlap layer 36, these cushion forming layers may then be placed over the wire spring assembly as shown.

Due to the fact that the reinforcing stiffening members 38 are interposed between the strip 40 and the overlying layer of cushion forming material such as the burlap sheet 36, the members 38 are held to the burlap sheet in spaced apart parallel relationship. In Fig. 4 each strip 40 is shown as folded to provide a fold 48 which extends parallel to the fold 42 and the opposite margin of the strip and projects upwardly from the strip. Each wire section 38 extends through the fold 48 and this insures the spacing apart of the wire sections along the strips in addition to their securement to the strips by having their ends bent over as at 44.

Figs. 6, 7 and 8 illustrate my spring liner employed with a different kind of wire spring assembly. It is apparent that this spring liner is suitable for use with any conventional wire spring assembly. In Fig. 1 coil springs of the hour-glass type are shown. In Figs. 6, 7 and 8 zigzag springs 50 are shown as secured to and extending between opposite sides of the boundary wire frame 52 by hob ring clips 54. In Fig. 1 the reinforcing stiffening members of my liner extend between the front and rear margins of the seat cushion. In Figs. 6 and 7 the stiffening members extend from end to end of the seat cushion. Either method of disposition is suitable.

In Fig. 7 the spring liner is of substantially the same character as that illustrated in Figs. 1, 2, 3 and 5 except that the wire sections 38 are longer and in addition to the strips 40 at the ends of the wire sections there are strips 41 which are arranged intermediately the strips 40. In this figure of the drawing, Fig. 9 illustrates a cross-sectional view and it will be noted that each strip 40 is folded over along its outer margin as at 42 and the end of the wire member 38 is bent thereover as at 44 all as described in connection with the construction shown in Figs. 1 and 3. In this construction also the upper surface of each strip 40 is coated with adhesive as shown in Fig. 5 and is adhesively secured to the overlying layer of burlap 36 as shown in Fig. 8 and as described in connection with the structure shown in the first five figures of the drawing.

Fig. 8 merely illustrates an adaptation of this liner to a zigzag spring assembly wherein there is an outer layer of upholstery fabric 30, a layer of netting 34, a layer of wadding 32 and an overlying layer of burlap 36. The intermediate longitudinal strips 41 are formed of two layers of burlap adhesively secured together between the members 38 so as to hold the members in spaced apart relationship. The upper surface of each of these layers 41 may be adhesively coated as are the layers 40 and as shown in Fig. 5 for adhesive securement to the overlying burlap layer 36.

Fig. 6 illustrates a slight modification wherein the reinforcing stiffening members are provided in the form of a reversely folded continuous wire indicated as 56 and the strips 40a and 41 are secured thereto as shown. The strips 40a correspond to the strips 40 previously described but each strip 40a is folded over the ends of the wire 56 as shown in Fig. 10 and adhesively secured together to securely hold the stiffening wire sections in place.

What I claim is:

1. An upholstery spring cover adapted to overlie a cushion spring assembly comprising, in combination, a plurality of reinforcing stiffening members disposed in a row in spaced apart substantially parallel relationship, a pair of flexible strips extending along the opposite margins of said row of members and thereunderneath, each strip being folded over along its outer margin, each member having its opposite ends bent over the folds of said strips, each strip provided with an upwardly projecting fold extending parallel to its marginal fold and spaced between its marginal fold and the opposite margin of the strip, each of said members extending through the upwardly projecting fold of each strip with both margins of the strips disposed underneath the members.

2. The invention as defined in claim numbered 1 characterized in that there is provided a sheet of flexible material overlying the assembly of reinforcing stiffening members and the pair of flexible strips to which such members are secured, and said strips are adhesively attached to the underside of said sheet spaced apart by the stiffening members which extend between the strips underneath said sheet.

NEWTON E. SHOCKEY.
